UNITED STATES PATENT OFFICE.

JESSE T. SHEETS, OF COVINGTON, KENTUCKY, ASSIGNOR OF ONE-HALF
TO SOL. P. KINEON, OF CINCINNATI, OHIO.

TELEGRAPH-KEY.

No. 830,253.

Specification of Letters Patent.

Patented Sept. 4, 1906.

Application filed November 9, 1905. Serial No. 286,446.

To all whom it may concern:

Be it known that I, JESSE T. SHEETS, a citizen of the United States of America, and a resident of Covington, county of Kenton, 5 State of Kentucky, have invented certain new and useful Improvements in Telegraph-Keys, of which the following is a specification.

The object of my invention is a telegraph-key by which the operator may open the circuit for sending messages simply by grasping the key, which automatically closes the circuit when released by the operator and which may be held in the position to keep the circuit open without interfering with the flexibility of the operator's arm and wrist while sending messages. This object is attained by the means described in the specification and illustrated in the drawings, in which—
10 Figure 1 is a plan view. Fig. 2 is a view, partially in side elevation and partially in section, through one of the binding-posts and through the contact-point. Fig. 3 is a detail plan view of the contact-strip for putting the 15 contact-point in contact with the binding-post, which is insulated from the frame. Fig. 4 is a detail view, partly in plan and partly in section, of the button, lever, and spring-arm which is mounted on the lever. Fig. 5 is a 20 perspective view, upon an enlarged scale, of the end of the spring-arm.
25 Figure 1 is a plan view. Fig. 2 is a view, partially in side elevation and partially in section, through one of the binding-posts and through the contact-point. Fig. 3 is a detail plan view of the contact-strip for putting the contact-point in contact with the binding-post, which is insulated from the frame. Fig. 4 is a detail view, partly in plan and partly in section, of the button, lever, and spring-arm which is mounted on the lever. Fig. 5 is a 30 perspective view, upon an enlarged scale, of the end of the spring-arm.

Referring to the parts, metallic frame A has the usual journal-bearings *a a'*, between which the lever B is fulcrumed upon the 35 frame. Binding-post C is in contact with the frame A, and binding-post C' and contact-point D are insulated from the frame. Binding-post C' and contact-point D are electrically connected by a metallic strip E. Lever 40 B is provided with the usual back-stop or limiting-screw *b* and coiled spring *b'* for holding the stud *b²* on the lever normally out of contact with the contact-point D.

A shaft F, upon the outer end of which 45 button *f* is secured, is journaled revolvably in the end of lever B and has an outwardly-projecting pin *f'*. Secured to a stud *b³*, projecting downward from the under side of lever B, is a spring-arm G, whose outer end 50 *g* is curved inward adjacent to shaft F and has a slot *g'*, through which pin *f'* passes, the extreme end of the lever G having a finger *g²* to contact a stud *b⁴*, projecting upward from the lever B. Spring-arm G has a tendency

to stand in contact with a regulating-screw 55 *d*, which passes through binding-post D. By rotating the shaft F by turning the button *f* the pin *f'* will carry the arm G out of contact with the screw *d*. When the button *f* is released, the elasticity of the arm G returns 60 the button to its normal position, as shown in Fig. 1, bringing the arm G into contact with the screw *d*.

In use it is seen that when the parts stand in their normal position (that shown in Fig. 65 1, wherein the arm G contacts screw *d*) lever B is in electrical communication with binding-post C' through the arm G, screw *d*, contact-point D, and strip E. It is seen likewise that by rotating the button *f* to cause 70 pin *f'* to carry arm G out of contact with the screw *d* the circuit is broken and is closed only when the lever B is depressed to bring the stud *b²* in contact with the contact-point D in the manner customary for sending messages and that when the operator releases button *f* the spring G automatically resumes 75 its normal position against the screw *d* to close the circuit.

The motion necessary to rotate the button 80 *f* to open the circuit, is very simple and the grip upon the button necessary to hold it in the position such that the pin *f'* keeps the spring G out of contact with the screw *d* is so slight and of such a character that it interferes 85 in no respect with the flexibility of the arm of the operator in sending messages.

What I claim is—

1. In a telegraph-key the combination of a frame, a contact-point and a binding-post 90 insulated therefrom, an electrical conductor connecting the contact-point and said binding-post, a main lever journaled in the frame, a button mounted revolvably on the lever, a spring-arm secured at one of its ends to the 95 lever standing normally in contact with the contact-point and having its free end adjacent to the button and means for coupling the button and the spring-arm whereby the rotation of the button carries the spring-arm 100 out of contact with the contact-point.

2. In a telegraph-key the combination of a frame, a main lever mounted therein, a contact-point and a binding-post insulated from the frame, a conductor connecting the binding-post and the contact-point, a button mounted revolvably on the lever, a spring-arm secured at one end to the lever, a regu-

lating-screw passing through the contact-point and normally contacting the spring-arm, a pin projecting from the button and engaging the free end of the spring-arm whereby the revolution of the button throws the spring-arm out of contact with the regulating-screw.

3. In a telegraph-key of the character described a lever having a spindle mounted revolu-

wardly from the spindle, a stud projecting upwardly from the lever in the path of the pin, a spring-arm secured to the lever at one end and at the other end bent inward to engage the stud and slotted to pass the pin.

JESSE T. SHEETS.
